UNITED STATES PATENT OFFICE.

DAVID JOHNSON, OF BURWELL, NEBRASKA.

HORSE-POWER.

SPECIFICATION forming part of Letters Patent No. 761,304, dated May 31, 1904.

Application filed January 22, 1904. Serial No. 190,216. (No model.)

To all whom it may concern:

Be it known that I, DAVID JOHNSON, a citizen of the United States, residing at Burwell, in the county of Garfield and State of Nebraska, have invented a new and useful Horse-Power, of which the following is a specification.

This invention relates to horse-power of the type in which motion imparted to a master-wheel by sweeps attached to the periphery thereof is transmitted through suitably-arranged gearing to a shaft rotatably mounted in the supporting-frame of the horse-power.

The principal object of the invention is to provide in a horse-power of the type specified an improved arrangement of power-transmitting gearing by means of which the strains imposed upon the master-wheel in operation are so distributed as to produce a balanced effect upon the master-wheel and to relieve the various parts of the supporting-frame of the horse-power of any localized excessive strain tending to distort the frame and interfere with the operation of the mechanism.

A further object of the invention is to provide an improved horse-power of the type specified in which the elements are so arranged that a minimum of wear will result from the use of the mechanism and the durability of the structure will be accordingly increased.

In attaining the objects above mentioned I prefer to make use of the novel construction and combination of parts of a horse-power, as hereinafter described, illustrated in preferred form in the accompanying drawings, and having the novel features thereof particularly set forth in the appended claims.

In the drawings, Figure 1 is a plan view of the improved horse-power. Fig. 2 is a view in transverse section.

Referring to the drawings, in which corresponding parts are designated by similar characters of reference throughout, F designates the supporting-frame of the horse-power, which is mounted on wheels W for convenience in transportation and is provided with a tongue T, by means of which the horse-power may be drawn from place to place by draft-animals. The frame F is of substantially

rectangular form, comprising longitudinal members 1 1 and transverse members 2 2, secured together in any suitable manner. The frame F affords support for a master-wheel 3, arranged for rotation in a horizontal plane and supported in any preferred manner. The master-wheel 3 is preferably double-cogged, as shown, so that it may be reversed from time to time to equalize the wear, and so prolong the life of the apparatus. In the construction illustrated the master-wheel 3 is supported upon slightly-tapered beveled pinions 4, mounted upon brackets 5, which are rigidly secured upon the frame F, and the master-wheel is held against lateral shifting by guide-rollers 6, arranged to turn on vertical axes, as shown, and mounted upon brackets 5 also.

Motion is imparted to the master-wheel by sweeps, (not shown,) which may be attached to the periphery of the master-wheel in any preferred manner and provided in any desired or convenient number. The power applied to the master-wheel is transmitted to slightly-tapered pinions 7 and 8, supported upon shafts 9 and 10, respectively. The shafts 9 and 10 are mounted in bearings fastened upon the frame F, and the motion imparted thereto by the pinions 7 and 8 is transmitted to a main driving-shaft 11, arranged transversely of the frame, as shown. The means employed for transmitting the motion of the shafts 9 and 10 to the main shaft 11 will now be described.

Rigidly mounted upon the main shaft 11 intermediate of its ends and arranged to turn in the longitudinal median plane of the frame F is a large double-beveled gear 12. With the teeth upon one face of the double-beveled gear 12 beveled pinions 13, mounted upon the shafts 9, are adapted to mesh, and the strain imposed upon the gear 12 by the pinions 13 is balanced by directly opposite strains imposed thereon by similar pinions 14, arranged to mesh with the teeth upon the other face of the gear 12 at points directly opposite the points of engagement of the pinions 13. The beveled pinions 14 are rigidly attached to shafts 15, supported in bearings upon the frame F, as shown. These shafts 15 also bear bev-

eled pinions 16, which mesh with similar pinions 17, which are fast to the shafts 10, above mentioned.

By means of the mechanism described in the foregoing paragraph the movement transmitted to the tapered pinions 7 by the master-wheel is transmitted directly to the double-beveled gear 12 by means of the beveled pinions 13, mounted upon the shafts 9, upon which the pinions 7 are secured; but the motion imparted to the pinions 8 is transmitted indirectly to the gear 12 through the intermediary beveled pinions 16 and 17. Consequently the rotation of the pinions 7 and 8, which is in the same direction, is applied to opposite sides of the double-beveled gear 12 in opposite directions, so that the strains imposed upon the double-beveled gear are balanced by being applied at opposite points; but the full effect of the power applied to the pinions 7 and 8 is realized in driving the gear 12. Furthermore, by placing the pinions 7 and 8 in the positions shown the strain upon one half of the master-wheel is balanced by an equal strain upon the other half, and there is no tendency to produce a lateral bodily movement of the entire master-wheel. In consequence of the equal distribution of the strains upon the master-wheel and the double-beveled gear 12 the strains upon the frame are also equalized and distributed in such manner that the frame is adapted to withstand them effectively without becoming distorted thereby.

In the operation of the horse-power the movement of the master-wheel is transmitted, through the gearing above described, to the main driving-shaft 11, and a steady uniform movement of the driving-shaft is obtained. This movement is transmitted from the driving-shaft to the machinery to be operated by means of any preferred form of power-transmitting devices. As any form of transmission mechanism adapted to the particular circumstances of any case may be employed to transmit movement from the shaft 11 to the machinery to be operated by the horse-power, the description and illustration of such transmitting devices are regarded as superfluous.

In the description of my invention I have limited myself to the principal features thereof and have omitted all detailed description of mere mechanical details of construction, which may be varied at will without departing from the spirit of the invention. In the construction of the frame F especially the arrangement of the interior elements may be varied to suit the whim of the constructor without departing from the spirit of the invention, and I have merely shown a conven-

ient arrangement of brackets and braces to hold the shafts and gears in operative relation.

In order to bring the horse-power to rest quickly and to prevent the sweeps from striking the draft-animals when it is desired to stop the horse-power, it is desirable to provide a brake of any ordinary type to operate directly upon the master-wheel at the inner margin thereof. In the form of the invention illustrated the brake comprises a block 20, arranged to slide in guides 21, supported in the frame F and preferably disposed in the plane of the gear 12. The block is operated by means of a pivoted brake-lever 22, projecting upward from the frame and preferably arranged to engage a segmental rack 23 to hold it in any desired position.

Having thus described the construction and operation of my invention, what I claim as new, and desire to secure by Letters Patent, is—

1. In a horse-power, a master-wheel, a main driving-shaft, a double-faced gear rigidly mounted upon said shaft, pinions meshing with both faces of said double-faced gear at diametrically opposite points, and suitable driving connections between said master-wheel and said pinions.

2. In a horse-power, a master-wheel, a main driving-shaft diametrically arranged within said master-wheel, a double-faced gear rigidly mounted upon said shaft, pinions meshing with both faces of said gear at diametrically opposite points, direct driving connections between the master-wheel and the pinions engaging one face of said double-faced gear, and indirect driving connections between the master-wheel and the pinions engaging the other face of said double-faced gear.

3. In a horse-power, a master-wheel disposed in a substantially horizontal plane, a main driving-shaft also disposed in a horizontal plane, a double-faced gear mounted on said driving-shaft, pinions engaging one face of said gear at diametrically opposite points, direct driving connections between said pinions and said master-wheel, pinions engaging the other face of said double-faced gear at points directly opposite the points of engagement of the first-mentioned pinions, and indirect driving connections between said last-mentioned pinions and the master-wheel.

In testimony that I claim the foregoing as my own I have hereto affixed my signature in the presence of two witnesses.

DAVID JOHNSON.
